N. S. Nodd & M. L. Gandyson of Troy, N. Y.

Assignors to

Sweet and Little of Crescent, N. Y.

Letters Patent No. 829. Dated August 26th 1856.

The schedule referred to in these Letters Patent and making part of the same.

To all whom it may concern:

Be it known, that we, N. S. Nodd and M. L. Gandyson, each of the City of Troy, in the County of Rensselaer, and State of New York, have jointly invented or produced a new and original design for certain plates of a Cooking Stove having an elevated oven, which we call the "Emperor"; And we do hereby declare that the following is a full and exact description of the same, reference being had to the annexed drawings, making a part of this specification, in which Fig. 1. is an elevation of the

Des. 829

front plate; Fig. 2, a section of the front plate at the line 2.2, in Fig. 1; Fig. 3, a section of the front plate at the line 4.4, in Fig. 1; Fig. 4, an elevation of the side plate; Fig. 5, a section of the side plate at the line x.x, in Fig. 4.—only showing the general curvature of the plate and its mouldings; Fig. 6, an elevation of the side or front plate of the elevated oven; Fig. 7, a section of the side plate of the elevated oven at the line w.w, in Fig. 6. Fig. 8, an elevation of the door of the elevated oven; and Fig. 9, a section of the border moulding of the door represented in Fig. 8. The same letters refer to like parts in all the figures.

The design of the end plate, consists of the ornaments A, at each end, and the compound ornament B, on each of its doors; that of the side plates, of the ornament A, on the narrow part of the plate, the compound ornament C, on its fire door, and the combination of ornaments D, on its fire door; that of the side plate of the elevated oven, of the combined gothic pillars, arch, mouldings and panels, at each end E, E, and of the compound ornament F, on the depressed central panel G, enclosed at the sides and top by the arched compound gothic moulding H, and at the bottom, by the ornamental work I; — the whole being surrounded by the broad moulding J; and that of the door of the elevated oven, of the complex arrangement of ornaments on the panel surrounded by the compound moulding K; — all the parts of the different ornaments of the several plates being framed and arranged together as represented in the annexed drawings.

What we claim as our invention or production, and desire to secure by letters patent, is, the ornamental design and configuration herein specified and represented in the annexed drawings, for the plates of a cooking stove having an elevated oven.
